UNITED STATES PATENT OFFICE.

ALFRED INGRAM AND HARRY INGRAM, OF BROOKLYN, NEW YORK, ASSIGNEES TO INGRAMS INCORPORATED, OF BROOKLYN, NEW YORK, A CORPORATION OF NEW YORK.

CLOSURE FOR JARS, BOTTLES, AND OTHER RECEPTACLES.

1,346,654.

Specification of Letters Patent. Patented July 13, 1920.

Application filed October 12, 1917. Serial No. 196,169.

To all whom it may concern:

Be it known that we, ALFRED INGRAM and HARRY INGRAM, citizens of the United States, and residents of Brooklyn, in the county of 5 Kings and State of New York, have invented certain new and useful Improvements in Closures for Jars, Bottles, and other Receptacles, of which the following is a specification.

10 The invention resides more particularly in a cap of tin or other suitable metal, with a special compressible gasket in the flange or skirt portion thereof, adapted to the effectual sealing of glass tumblers, jars and other 15 containers or receptacles having smooth exterior surfaces of substantially rigid or unyielding character.

One purpose of the invention is to provide 20 a cap and gasket readily capable of being effectually sealed against the exterior surfaces of a glass tumbler or like container by pressure applied downwardly and annularly against a beaded portion of the skirt of the cap holding the gasket to be compressed 25 against the exterior surface or wall of the container.

Glass tumblers and like containers are difficult to properly seal owing to defects in the upper edge portions thereof due to the 30 conditions under which such containers are manufactured, and as an illustration we may mention that the upper exterior surfaces of the container, while intended to be straight, are frequently tapered, and also 35 that while the upper portions of such containers are supposed to be true they frequently have irregularities in their surfaces and in many instances have what are called "crizzles," which are very fine grooves or the like 40 sometimes almost imperceptible to the eye or touch, but quite sufficient to prevent, under many conditions, the hermetic sealing of the container by many of the closures at the present proposed. One of the principal 45 purposes of our invention is to provide a closure which may be utilized in the effectual sealing of a container, regardless of the usual irregularities in the exterior surfaces of the upper end portion thereof and regardless of 50 such irregularities and crizzles as may be present along the upper edges of the container.

In carrying out our invention we provide

a metal cap adapted to pass downwardly over the upper end of the container and having a depending encompassing flange or skirt portion which is shaped or grooved to receive the gasket or packing ring, said flange or skirt portion having a plain upper peripheral section and the groove or beading in said flange being located below said plain section and projecting on annular lines outwardly from the vertical plane thereof and adapted to receive the gasket or packing ring. The cap and gasket or packing ring are of such dimensions with relation to the upper outer portions of the container that they closely fit upon the same when applied thereto, and thereafter the sealing is effected by a downward pressure 70 against the upper outer portions of the beaded section of the flange, whereby said section and the gasket or packing ring contained therein are pressed downwardly and inwardly toward the outer walls of the container, with the result that the said gasket or packing ring becomes greatly compressed 75 against the walls of the container and is held in such condition and position by the beaded section of said flange, said gasket or packing ring then providing an effectual seal of adequate area regardless of the usual irregularities that may be present in the container. The compression of the beaded section of the flange or skirt portion of the 80 cap and the gasket or packing ring held thereby also results in the lower edges of the packing ring being squeezed downwardly below said section of the cap, and this is important since by reason thereof a person desiring to open the receptacle may, with a fork or other instrument, draw the packing ring downwardly from the cap, thus breaking 85 the seal and permitting the cap to be conveniently removed.

The invention may be carried out in several ways, two of which are shown in the accompanying drawings, and said invention will be fully understood from the detailed description hereinafter presented, reference 90 being had to the aforesaid drawings, in which:

Figure 1 is a side elevation, partly broken away and partly in section, of a glass tumbler having a cap and gasket applied thereon embodying our invention, the cap and

gasket being illustrated in their initial condition or before the sealing step of the process has taken place;

Fig. 2 is a like view of the same showing 5 the relation of the cap, gasket and tumbler, after the beaded section of the flange or skirt portion of the cap has been driven downwardly and inwardly, to compress the gasket against the container;

10 Fig. 3 is a vertical section of a fragmentary portion of the container, cap and gasket in their initial relation, together with a sectional portion of a cylindrical tool by which the beaded section of the flange or 15 skirt portion of the cap and the gasket or packing ring held thereby, may be pressed inwardly and downwardly toward the container or to the condition shown in Fig. 2;

Fig. 4 is a like view of the same showing 20 the relation of the parts when the applying tool has been driven downwardly to compress the gasket against the container;

Fig. 5 is a sectional fragmentary view corresponding with Fig. 3, but illustrating a 25 modified form of the beaded section of the flange or skirt portion of the cap, and

Fig. 6 is a like view of the same showing 30 the relation of the parts after the applying tool has been driven downwardly against the beaded section of the flange or skirt portion of the cap to compress the gasket held thereby against the exterior surfaces of the container.

In the drawings, referring to Figs. 1 to 4 35 inclusive, 10 designates a container, which may be a glass tumbler, 11 the cap, 12 a downwardly depending flange or skirt constituting a portion of said cap and in its upper part adapted to closely fit upon the upper exterior portion of the container, 13 an annular beading formed in the lower portion of said flange or skirt, and 14 the gasket disposed within the groove formed in said beading and adapted to engage the exterior wall of the container 10.

The container 10 has plain exterior walls, and the cap 11 is adapted to close the upper end of the container and at the upper portion of its flange or skirt 12 to snugly 50 compass the upper outer walls of the container. The beading or grooved portion 13 of the cap may be of varied formation, but the preferred construction thereof is illustrated in Figs. 1 to 4 inclusive, in which it 55 may be seen that the upper portion of the beading 13 has a wall 15 which diverges downwardly and outwardly in a direction from the container and that from the lower outer edges of said wall 15 a vertical wall 16 or flange 16 extends downwardly and sets outwardly from the side wall of the container. The normal condition of the walls 15, 16 constituting the beading 13 is shown in Figs. 1 and 3, and within said beading is 60 located the compressible vertically elongated 65

gasket or packing ring 14 having an upper downwardly and outwardly inclined surface corresponding with the wall 15 of the beading 13 and an outer vertical surface matching the vertical portion or section 16 of the 70 beading 13. Normally the lower edge of the beading 13 may be turned inwardly to a slight extent, as shown in Figs. 1 and 3, so as to facilitate the assembling of the cap and gasket and the application of the same 75 in assembled condition upon the container.

In accordance with our invention we depress the beading 13 and gasket 14 downwardly and inwardly toward the container and at the same time materially elongate the 80 same, the gasket being elongated by its compression inwardly to a materially reduced thickness, and the beading being elongated by having its walls depressed downwardly and moved inwardly toward the container. 85 The gasket and beading are by the method of applying the closure to sealing position, transformed from the condition in which they are represented in Fig. 3 to that illustrated in Fig. 4. The compression of the 90 gasket 14 results in the lower edges thereof being protruded below the lower edge of the beading 13, and this has the beneficial effect of so exposing a portion of the gasket that by means of a fork or other convenient 95 means the gasket may be extracted downwardly from the beading when it is desired to remove the cap from the container. The beading 13 is open at its lower end and thus no difficulty is experienced during the compression of the beading and gasket in causing a portion of the lower edges of the gasket to become exposed below the beading.

The preferred method of compressing the beading 13 and gasket 17 downwardly and 100 inwardly toward the container is indicated in Figs. 3 and 4 and comprises the employment of a cylindrical tool or die 17 having its lower inner edges inclined downwardly and outwardly, as at 18, and its surface 105 above said inclined portion 18 vertical, as at 19. The die 17 is cylindrical and hollow and of the requisite predetermined inner diameter to effect, when moved downwardly on the cap, the compression of the beading 110 13 and gasket 14 downwardly and inwardly or transform the same from their condition represented in Fig. 3 to that illustrated in Fig. 4.

We deem it of importance that the beading 13 is below an upper plain section or portion 20 of the flange 12 and that the lower edges of said beaded portion 13 are open and away from the container so that the gasket may be caused to protrude downwardly below the said beaded portion when the cap is in final position on the container. The walls of the container are unyielding, and hence with a cap and gasket of the character shown and described we are enabled 115 120 125 130

to secure a very effectual sealing of the container and one which is efficient notwithstanding any irregularities, crizzles or the like that may be present around the upper edges of the container. The closure of our invention is entirely efficient whether the walls of the container are straight or beveled. In the manufacture of some of these containers an attempt is made to have the upper exterior surfaces of the container vertical, but due to many conditions these vertical surfaces are not always present in containers as supplied to packers, and when they are not present the sealing, by the means heretofore employed, is not always effectual. In accordance with our invention we provide a seal which may be effectually applied to a container possessing many of the usual defects which are common to these containers, and it may readily be noted that the downward and inward pressure of the beading 13 and gasket 14 will make an efficient seal regardless of whether the upper exterior walls of the container are vertical or tapered.

In Figs. 5 and 6 we illustrate a modified form of the closure, and therefore in these figures number the cap 22, its flange or skirt portion 23 and its beading 24. Within the beading 24 is formed an angular groove holding a gasket or packing-ring 25 which is of oblong shape in cross-section, being thicker vertically than in width. The lower end of the beading 24 is open so that finally the gasket may have a portion of its lower edges squeezed downwardly therefrom, and the metal at the lower outer edge of the beading 24 may be flanged inwardly to a slight extent to facilitate the assembling of the cap and gasket and the application of the same in their assembled condition upon the container 10. The normal condition and relation of the beading 24 and gasket 25 are illustrated in Fig. 5, while in Fig. 6 the said beading and gasket are shown in the relation they occupy after they have been acted on by the tool or die 17 to compress the beading and gasket downwardly and inwardly toward the exterior wall of the container, the said beading and gasket being, during and by this operation, vertically elongated and the lower edges of the gasket squeezed from the lower edges of the beading, so that said edges of the gasket become exposed, as in the construction shown in Fig. 4. When the beading 24 and gasket 25 are moved downwardly and inwardly toward the container by means of the die 17, said beading and gasket take substantially the outline illustrated in Fig. 4, as will be understood on reference to Fig. 6.

Our invention comprises the cap having the lower beading in its flange or skirt and a gasket within said beading, said beading being open at its lower end and said bead-

ing and gasket being adapted to be subjected to downward and inward pressure tending to vertically elongate them and compress the gasket with sealing effect against both the container and lower portions of said flange or skirt. 70

The invention admits of variations in construction and hence we do not confine the invention to details otherwise than the appended claims may require. 75

What we claim as our invention and desire to secure by Letters Patent, is:

1. In combination with a receptacle having plain exterior surfaces, a side seal closure of the character described therefor comprising a cap adapted to seat on the top of the receptacle and having a depending flange or skirt portion adapted to encompass the exterior surfaces of the receptacle at the upper end thereof and formed with an upper plain section adapted to closely engage said exterior surfaces and a lower beaded section set outwardly from the surface of the receptacle and open at its lower end and comprising a lower vertical section and a top which extends outwardly in a lateral direction from the said upper plain section of the flange, and a gasket in said beaded section, said beaded section and gasket being adapted to be vertically elongated in a downwardly direction by pressure applied against the upper edge of said beaded section to press said section and said gasket downwardly and also inwardly toward the receptacle and bind said gasket against the outer plain walls of the receptacle. 90

2. In combination with a receptacle having plain exterior surfaces, a side-seal closure of the character described therefor comprising a cap adapted to seat on the top of the receptacle and having a depending flange or skirt portion adapted to encompass the exterior surface of the receptacle at the upper end thereof and formed with an upper plain section adapted to closely engage said exterior surfaces and a lower beaded section set outwardly from the surface of the receptacle and open at its lower end and comprising a lower vertical section and a top which extends outwardly in a lateral direction from the said upper plain section of the flange, and a gasket in said beaded section, said beaded section being vertically elongated in a downwardly direction and reduced in diameter against the gasket by the downward deformation of said top of said beaded section and holding by such elongation said gasket vertically elongated in a downwardly direction and firmly compressed against the plain walls of the receptacle below the upper plain section of the flange of the cap. 115

3. In combination with a receptacle having plain exterior surfaces, a closure of the 130

- character described therefor comprising a cap having a depending flange or skirt portion adapted to encompass the exterior surfaces of the receptacle at the upper end thereof and formed with an upper plain section adapted to closely engage said exterior surfaces and a lower beaded section set outwardly from the surface of the receptacle and open at its lower end and comprising a lower vertical section and a top which extends outwardly in a lateral direction from the said upper plain section of the flange, and a gasket in said beaded section, said beaded section being vertically elongated in a downwardly direction and reduced in diameter against the gasket by the downward deformation of said top of said beaded section and holding by such elongation said gasket vertically elongated in a downwardly direction and firmly compressed against the plain walls of the receptacle below the upper plain section of the flange of the cap, with the lower edges of the gasket exposed below said beaded section.
- 25 4. In combination with a receptacle having plain exterior surfaces, a side-seal closure of the character described therefor comprising a cap adapted to seat on the top of the receptacle and having a depending flange or skirt portion adapted to encompass the exterior surfaces of the receptacle at the upper end thereof and formed with an upper plain section adapted to closely engage said exterior surfaces and a lower beaded section set outwardly from the surface of the receptacle and open at its lower end and comprising a lower vertical section and a top which extends outwardly in a lateral direction from the said upper plain section of the flange, and a gasket in said beaded section, said beaded section being in the condition of having its lateral top bent downwardly and its side walls thereby moved inwardly against the gasket and toward the receptacle and holding said gasket vertically elongated in a downwardly direction and compressed against the plain walls of the receptacle and with its lower edges exposed below said beaded section.
- 35 5. In combination with a receptacle having plain exterior surfaces, a side-seal closure of the character described therefor comprising a cap adapted to seat on the top of the receptacle and having a depending flange or skirt portion adapted to encompass the exterior surfaces of the receptacle at the upper end thereof and formed with an upper plain section adapted to closely engage said exterior surfaces and a lower beaded section set outwardly from the surface of the receptacle and open at its lower end and comprising a lower vertical section and a top which extends outwardly and downwardly from said upper plain section of the flange, and a gasket in said beaded section having an inner face against the plain walls of the receptacle and an outer

face conforming to said beaded section, said beaded section and gasket being adapted to be vertically elongated in a downwardly direction by pressure applied against the upper edge of said beaded section to press said section and said gasket downwardly and also inwardly toward the receptacle and bind said gasket against the outer plain walls of the receptacle.

5. In combination with a receptacle having plain exterior surfaces, a side-seal closure of the character described therefor comprising a cap adapted to seat on the top of the receptacle and having a depending flange or skirt portion adapted to encompass the exterior surfaces of the receptacle at the upper end thereof and formed with an upper plain section adapted to closely engage said exterior surfaces and a lower beaded section set outwardly from the surface of the receptacle and open at its lower end and comprising a lower vertical section and a top which extends outwardly in a lateral direction from the said upper plain section of the flange, and a gasket in said beaded section, said beaded section being in the condition of having its lateral top bent downwardly and its side walls thereby moved inwardly against the gasket and toward the receptacle and holding said gasket vertically elongated in a downwardly direction and compressed against the plain walls of the receptacle and with its lower edges exposed below said beaded section.

Signed at Brooklyn, in the county of Kings, and State of New York, this 11th day of October, A. D. 1917.
